UNITED STATES PATENT OFFICE.

FRED STAPLES, OF NEGAUNEE, MICHIGAN, ASSIGNOR TO NEGAUNEE MECHANICAL SHOVEL COMPANY, OF NEGAUNEE, MICHIGAN, A CORPORATION OF MICHIGAN.

CAR LOADER.

Application filed May 24, 1923. Serial No. 641,140.

To all whom it may concern:

Be it known that I, FRED STAPLES, a citizen of the United States, and a resident of Negaunee, county of Marquette and State 5 of Michigan, have invented certain new and useful Improvements in Car Loaders, of which the following is a specification.

My invention relates to loaders of the type which are adapted to scoop up and load material into cars, and has reference more particularly to improvements in the loader shown and described in Letters Patent, 1,366,201, granted June 18, 1921, to John Mayne.

15 The principal objects of my invention are to increase the stability of the loader, by lowering the center of gravity thereof in the working position; to secure the loader more firmly onto the track; to provide improved means for advancing the loader along the track as the work progresses; to improve the dipper hoisting mechanism; to facilitate the placing of the car to be loaded on the loading device as well as the removal 20 thereof; and in general, to simplify the construction and increase the durability and efficiency of the loader.

On the drawings:

Fig. 1 is a top view of a loader embodying my improvements;

Fig. 2 a side view of the loader in the working position;

Fig. 3 a sectional view on the line 3—3 of Fig. 1;

Fig. 4 a detail view showing the manner of advancing the loader along the track as the work progresses;

Fig. 5 an enlarged sectional view on the line 5—5 of Fig. 4; and

40 Fig. 6 a fragmentary view, with parts in section, showing the loader mounted on its removable truck for transportation.

Referring to the drawings, the reference numeral 1 indicates the base of the machine 45 which preferably consists of a flat heavy plate, and supports the main structure of the loader which is preferably provided with a heavy bottom plate or platform 2 which is pivoted on the base plate 1 by means of 50 the king pin 3, so that the latter plate serves as a turn table to permit the loading device to be swung around to different positions. Any suitable construction may be provided for affording the desired freedom of rotation of the plate 2, for example, the upper

and lower bearing plates 4 and 5 which are secured respectively to the top plate 2 and base plate 1 and have a circular series of ball bearings 6 interposed therebetween in a suitable raceway.

60 This loader is designed for use in connection with a track consisting of a pair of properly spaced rails 7, upon which cars 8 which are to be loaded are brought up to and taken away from the loader, said cars 65 being adapted to be mounted on the top plate 2 of the device when they are to be loaded. To this end a pair of rails 9 are mounted on the plate 2 and spaced apart the same distance as the rails 7, the rails 9 70 preferably consisting of angle irons mounted on the brackets 10, which latter may be reversed to afford a track of different widths to correspond to the gauge of the cars 8 and track 7 in the particular place where the 75 loader is to be used.

The dipper supporting and operating mechanism, aside from the form of the dipper itself and the hoisting mechanism, is substantially the same as that of the Mayne 80 patent above referred to, and comprises a pair of horizontally disposed crowding cylinders 11 which are secured respectively along the sides of the plate 2 immediately adjacent the upturned edge portions or side 85 flanges 12 thereof, and each cylinder has a piston 13 therein with a piston rod 14 projecting from the forward end of the cylinder and horizontally pivoted to the side arms of the frame 15, which latter has the 90 dipper 16 secured to the forward end. An air supply pipe 17 controlled by the main valve 18 is connected to a suitable source of air supply through a pipe line consisting in whole or in part of the hose 19, said pipe 17 95 being extended upwardly at the side of the device so that operating valves are conveniently accessible to the operator, and this pipe 17 has a pipe 20 connected to the upper end and leading through the valve 21 to the pipes 22 and 23 which are connected to the rear ends of the cylinders 11. The valve 21 is of any suitable form which may be optionally adjusted to afford communication from the main pipe 17 to the pipe 20 for 100 forcing the pistons 13 forwardly in the cylinders 11, or may be adjusted to interrupt such communication and afford an exhaust opening from the pipe 20 to exhaust the air from the cylinders 11.

Mounted on the top plate 2 between the rails 9 are a pair of hoisting cylinders 24 with pistons 25 therein having forwardly extending piston rods 26 connected to the cross head 27; which latter carries the sheave 28. An upright frame 29 is mounted at the forward end of the top plate 2 and supports a sheave 30 at an elevation so that the lower portion of said sheave is substantially at the same level as the upper portion of the sheave 28. There is also a sheave 31 at the top of the frame 29. A cable 32 has one end attached to a suitable fastener 33 on the top plate 2 of the machine, and is passed forwardly around the sheave 28, then rearwardly around the sheave 30, then upwardly over the sheave 31 and has the other end connected to a bracket 34 on the rear of the dipper 16. Braces 35 at opposite sides of the machine connect the upper portion of the frame 29 to the side flanges 12 of the top plate 2 at points remote from the forward end of the machine to reinforce the frame 9 sufficiently to sustain the lifting strains imposed thereon in the operation of lifting the dipper.

A branch pipe 36 is also connected to the upper end of the pipe 17 and leads through a valve 37 similar to the valve 21, to the rear ends of the cylinders 24 for supplying pressure to force the pistons 25 forwardly in the cylinders.

In the operation of this device, the car 8 is run up onto the rails 9 to the position shown by dotted lines at 8 in Fig. 2, said rails 9 being preferably inclined rearwardly as indicated by dotted lines in Fig. 2, to facilitate removal of the loaded car from the loader, and in order to hold the car in place during the loading operation, an eye 38 is provided on each of the cars which is engaged by a hook 39 on the frame 29. When the car is in place, the air is first admitted to the crowding cylinders 11 by operating the valve 21 to force the dipper 16 forwardly onto the pile of material which is to be loaded into the car. When the dipper 16 is filled, the valve 21 is turned to the exhaust position, and the valve 37 operated to admit air into the hoisting cylinders 24. This forces the cross head 27 forwardly and exerts a pull on the cable 32, the first effect of which is to force the pistons 13 rearwardly in the crowding cylinders 11. When the latter reach the limit of their rearward movement the further operation of the pistons 25 causes the cable 32 to swing the dipper frame 15 on the pivots 40, thereby lifting the dipper to the upright position shown by dotted lines in Fig. 2. The rear end of the dipper 16 is formed with an inclined wall 41 which in the upright position of the dipper extends rearwardly and downwardly and projects over the forward end of the car 8, so as to dis-

charge the contents of the dipper into the car, such discharge being facilitated by proper operation of the elevating mechanism to cause the dipper frame to impact against the top of the frame 29 so as to throw the contents of the dipper back toward the rear end of the car. By proper manipulation of the valve 37 which controls the hoisting mechanism, the contents of the dipper can be distributed throughout the car as desired.

In the working position the base plate 1 rests directly on the rails 7 as shown in Fig. 2, the latter being provided on the under side with pairs of angle plates 43 near the front and rear respectively which depend at the side of the rails and prevent lateral shifting of the loader on the rails. To hold the device against rearward movement along the rails 7 as the dipper 16 is forced against the material to be taken up, the base plate 1 is provided at the front corners with connector plates 44 to which chains 45 are attached, and these chains are suitably connected to the framework of the tunnel or otherwise secured so as to hold the loader against reverse movement.

For directing the car 8 from the rails 7 up onto the rails 9 of the loader, a detachable runway 46 is provided comprising a pair of short rails which are spaced apart the same distance as the rails 9 and 7, and the rails of this runway 46 have apertures at their upper ends to engage pins 47 on the rear end of the plate 2 for holding the rails of the runway 46 in alignment with the rails 9. The top plate 2 as above indicated, swings on the base plate 1 around the pin 3 as a center, and the rails of the runway 46 which have their lower ends tapered so as to fit properly on top of the rails 7 may be readily adjusted, by swinging the top plate 2, so as to register with the rails 7.

For transporting the loader from place to place, the truck 42 is provided, and this has suitable sockets 48 in the top to receive the depending portions of the angles 43 to hold the loader in place on the truck, and it also has a socket 49 for the lower end of the pin 3. When the loader is in operation the truck is of course removed, so that the loader rests directly on the rails 7, and the truck may be found convenient for trammimg timber or transporting other materials along the track 7.

As the work progresses, it is necessary to advance the loader from time to time, and for this purpose I have provided a device which may be interlocked with the rails 7 so as to provide a stop against which the dipper 16 may be engaged, so that the crowding cylinders may be utilized for effecting the advance movement of the loader. This device comprises a pair of blocks or

clamps 50 which are slotted so as to fit down over the rails 7, said slots being enlarged at opposite sides near the upper extremities thereof as shown in Fig. 5. These blocks 5 are provided with upward extensions at one side which are connected by the chain 51.

To advance the loader along the track the dipper is first elevated to the position shown by dotted lines in Fig. 2, after which the 10 loader is swung around 180° on the base plate 1 so that it faces in the opposite direction. The dipper 16 is then lowered to the elevation of the track and the clamping device 50—51 engaged with the rails 7 so that 15 the chain 51 lies over the point of the dipper. Air is then admitted to the crowding cylinders 11 which tend to force the dipper rearwardly. This imposes a tension on the chain 51 and twists the blocks 50 around on 20 the rails, thereby causing them to grip the rails, and as the dipper is then restrained against rearward movement, the action of the crowding cylinders forces the loader forwardly along the rails 7, the angle plates 25 43 serving as guides to hold the loader on the rails. When the loader has been advanced sufficiently the slack is taken up in the chains 45 or the latter are connected to further advance timbers of the tunnel, and 30 the dipper 16 is then withdrawn from engagement with the clamping device 50—51 and elevated, after which the loader is swung around so as to again face forwardly.

35 With this device it will be noted that in the operative condition of the loader the tracks 9 are elevated only a short distance above the rails 7 so that the cars 8 may be run up onto the loader without difficulty, 40 and the loaded cars removed without danger of tipping or spilling the contents of the car, the removal of the loaded car being facilitated by the inclination of the rails 9 which gives the car a tendency to roll off of 45 the loader under its own weight when the hook 39 is disengaged from the eye 38.

50 While I have shown and described my invention in a preferred form, I am aware that various changes and modifications may be made without departing from the principles of my invention, the scope of which is to be determined by the appended claims.

I claim as my invention:

1. In an apparatus of the class described, 55 the combination of a platform having a framework extending upwardly therefrom at one end, a pair of crowding cylinders at opposite sides of the platform having piston rods projecting forwardly therefrom, a 60 frame horizontally pivoted to the forward ends of the pistons and having a dipper at the outer end, a pair of hoisting cylinders mounted on the platform between the crowding cylinders and having piston rods 65 projecting from the forward ends thereof,

a cross head connecting the forward ends of said latter piston rods and having a sheave mounted thereon, a cable connected to the dipper and engaging said sheave for operation by the forward movement of the 70 pistons of the hoisting cylinders to lift the dipper and its supporting frame to an upright position, and a pair of rails on the platform between the hoisting cylinders and the crowding cylinders adapted to support 75 a car in position to receive the contents of the dipper when the latter is thrown to the upright position.

2. In a device of the class described, the combination of a platform having an upright frame at the forward end, a pair of vertically spaced sheaves on the upright frame, a pair of horizontal hoisting cylinders mounted on the platform and having piston rods extending forwardly therefrom, 80 a cross head connecting the forward ends of said piston rods and provided with a sheave thereon, a reciprocable dipper frame horizontally pivoted at the forward end of the platform and having a dipper secured to the outer end, and a cable looped around the sheave on the cross head and engaging the vertically spaced sheaves on the upright frame and having one end fixed and the other end connected at the forward end of 85 the pivoted dipper frame.

3. In a device of the class described, the combination of a platform having an upright frame at the forward end, a dipper frame horizontally pivoted at the front of the platform, means for reciprocating said dipper frame to and from the platform, hoisting mechanism connected at the forward end of the dipper frame for swinging the latter to an upright position in front of 100 the aforesaid upright frame, a dipper on the forward end of the dipper frame having a rear wall angularly disposed so as to incline rearwardly and downwardly over the upright frame when the dipper frame is in the upright position, and a pair of rails on the platform for supporting a car in position to receive the contents of the dipper when the latter is in the elevated position. 105

4. In an apparatus of the class described, 110 the combination of a track, a frame structure mounted on the track and having a track section thereon adapted to receive a car thereon from the first mentioned track, a dipper reciprocable to and from the frame and adapted to be swung upwardly to discharge the contents into a car on the track section, and a truck operable on the first mentioned track and adapted to be removably interposed between said track and the 115 frame structure.

5. In a device of the class described, the combination of a track, a truck operable on the track, a frame adapted to be optionally mounted on the track or the truck, means 120

- on the frame for optionally engaging the track or the truck for holding the frame against displacement thereon, a track section on the frame adapted to receive a car thereon from the first mentioned track, a dipper mounted on the frame, and mechanism for operating the dipper to scoop up a quantity of material and deposit same in the car on the frame.
6. In a device of the class described, the combination of a track, a frame movable along the track, a dipper mounted on the frame, hoisting and reciprocating mechanism for operating the dipper to scoop up and discharge a quantity of material, and means for connecting the dipper with the

track whereby operation of the dipper reciprocating mechanism forces the frame along the track.

7. In a device of the class described, the combination of a track, a supporting base movable along the track, a frame rotatable on the base around a vertical axis, a dipper mounted on the frame, mechanism for reciprocating the dipper to and from the frame, and a rail clamping device at the rear of the device adapted to be engaged by the dipper in its reversed position so that operation of the reciprocating mechanism forces the loader forwardly along the rail.

FRED STAPLES.
